R. M. Wade,

Lubricator.

N° 11,024.

Patented June 6, 1854.

UNITED STATES PATENT OFFICE.

ROBERT M. WADE, OF WADESVILLE, VIRGINIA.

LUBRICATOR.

Specification of Letters Patent No. 11,024, dated June 6, 1854.

To all whom it may concern:

Be it known that I, ROBERT M. WADE, of Wadesville, in the county of Clarke and State of Virginia, have invented a new and useful 5 Improvement in Oil-Cups for Locomotive and other Steam Engines; and I do hereby declare that the following is a full, clear, and exact description of the construction and operation of the same, reference being 10 had to the annexed drawing forming part of this specification, in which—

Figure 1 is a front elevation of the oil cup. Fig. 2 is a side elevation of the same. Fig. 3 is a section on line $\alpha\alpha$ of Fig. 2 and 15 perpendicular to the axis of the plug.

Similar characters of reference denote the same part.

The object of my invention is to so arrange the several parts of the lubricator that 20 the engineer may supply and discharge the feed cylinder by means of a rod leading from the arm of said cylinder to a position within his reach.

The invention consists in constructing in 25 the feed cylinder two separate openings, one for feeding and the other for discharging; the relative position of these openings being such that when one is performing its functions the communication between the 30 other and its corresponding passage will be cut off, either opening being brought into operation by the movement of the cylinder, arm within certain limits, produced by a rod connected with said arm and leading to 35 a position near the engineer's stand, so that the oil may be admitted to the steam cylinder at all times without the necessity of the engineer leaving his stand.

To enable others skilled in the art to make 40 and use my invention I will proceed to describe its construction and operation.

In the drawing A is a hollow cylindrical chamber to contain the oil or other lubricant. The outer surface of this cylinder is 45 ground so as to closely fit the cylinder or jacket B, and be capable of turning within and in close contact with the same. Leading from the cylinder B are the branches C, D, the former containing the channel c leading 50 to the cup or reservoir E and the latter furnished with the channel d leading to the steam cylinder, to which the apparatus is attached by the screw thread f . The cylinder or hollow plug A is furnished with 55 two openings a and b , the former intended to admit oil to the plug and the latter for

the delivery of the same through the passage d . The openings are so situated as shown in Fig. 3 that when one a is in communication with the channel c the other will be 60 closed by the inner surface of the jacket B, and all communication with the steam cylinder cut off, while if the opening b communicate with the channel d and the oil flow to the steam cylinder the outer surface of the 65 plug A will close the channel c and all communication between the reservoir E and the chamber A will be cut off.

Attached to the outer face or projecting portion of the plug A is the arm F for turning said plug, the amplitude of the movements being governed by the studs P P', between which the arm is at liberty to oscillate, the studs being so placed that when the lever F is in contact with either stud one 70 of the openings a b will perform its functions. From the extremity of the lever F a rod R is carried to a position within reach of the engineer, so as to place the movement of said lever at all times under his control, 75 without the necessity of his leaving his stand. This effective action of the apparatus by the slight movement of the lever F is due to the construction of the cylinder A with the two openings a and b , relatively 80 situated as herein described, for with but one aperture, as these cups are generally constructed, it would be impossible to operate them with a rod, as the operating position of the opening at both feed and discharge, would necessarily be a dead point 85 of the crank and rod, making the rotation of the cylinder A by power applied to the rod an impossibility.

What I claim as my invention and desire 90 to secure by Letters Patent, is—

The hollow cylinder A in combination with the jacket B, constructed and operated as herein before set forth, namely, the two apertures in the cylinder being so situated 100 that while the upper one is admitting oil into the cylinder, the lower one is closed to the steam, and when the lower aperture is open to the steam, the upper one is closed to the steam and to oil in the cup.

In testimony whereof, I have hereunto signed my name before two subscribing witnesses.

ROBT. M. WADE.
